UNITED STATES PATENT OFFICE.

HARRISON H. BOYCE, OF JERICHO, NEW YORK.

DESIGN FOR A MOTOR-HEAT INDICATOR.

Application filed March 25, 1927. Serial No. 21,343. Term of patent 14 years.

To all whom it may concern:

Be it known that I, HARRISON H. BOYCE, a citizen of the United States, and a resident of Jericho, county of Nassau, Long Island, New York, have invented a new, original, and ornamental Design for a Motor-Heat Indicator, of which the following is a specification, reference being had to the accompanying drawings, forming a part hereof.

Referring to the annexed sheet of drawings,

Figure 1 represents a front elevation of my design for a motor heat indicator, made in accordance with my new design; and

Figure 2 is a side view thereof.

I claim:

The ornamental design for a motor heat indicator, substantially as shown.

HARRISON H. BOYCE.
